UNITED STATES PATENT OFFICE.

WILLIAM E. SHERBONDY, OF CLEVELAND, OHIO.

SUCTION CLEANER.

Application filed August 14, 1923. Serial No. 657,294.

This invention relates to suction cleaners of the type wherein a suction fan derives its power from the wheels on which the cleaner is supported.

5 In the manufacture of suction cleaners of the character referred to, considerable difficulty and expense are incurred in obtaining accuracy in the alignment of the various cooperative power transmitting parts constituting the mechanical motor, whereby, when the fan is rotated by power derived by a starting impulse obtained from the suction cleaner wheels when the cleaner is moved in one direction, a sufficiently high 15 speed will be imparted to the fan to cause the same to rotate during a subsequent period in which the cleaner and incidentally the driving wheels are being moved in an opposite direction. This of course, is an 20 essential requirement in suction cleaner motors of the mechanical type, wherefore the general object of the present invention is the provision of a novel arrangement of the fan propeller mechanism and the fan as 25 well as the driving wheels upon a single housing member forming only a small portion of the entire cleaner casing, whereby an extreme degree of accuracy may be obtained in manufacturing the cleaners without 30 increasing the expense thereof. To this end, I arrange the driving wheels, the housing, propeller shaft and fan in the nature of a unitary cooperative mechanism readily attachable to that portion of the cleaner casing comprising the nozzle and fan housing.

In conjunction with the foregoing object, there is another object of my invention which is directed to the provision of a suction cleaner casing which will offer a minimum 35 resistance to the suction action of the fan and the movement of extraneous, collected particles. Hence, I make provision for unusually large, unobstructed passageways from the nozzle opening to the fan casing and from the fan casing through a dust bag exhaust port positioned at a low level relative to the nozzle intake whereby only a minimum lift is required to deposit the dust in the bag. This I accomplish without interfering with the economy and accuracy in manufacture afforded by the above related 45 50 arrangement.

A more specific object of my invention is the provision of a simplified form of gearing and clutch mechanism for a fan motor 55 of the character referred to, which may be directly associated with the driving wheels of the cleaner and the supporting shaft therefor.

Other objects will hereinafter be set forth 60 in the following description which refers to the accompanying drawings illustrating a preferred embodiment thereof. The essential characteristics of my invention are summarized in the claims.

In the drawings, Fig. 1 is a side elevation of a suction cleaner of the mechanically driven type and which embodies the novel features of my invention; Fig. 2 is a cross-sectional plan view taken substantially along the line 2—2 of Fig. 1 and showing the manner in which I prefer to support the fan shaft on a detachable portion of the cleaner casing; Fig. 3 is a cross-sectional elevation taken substantially along the line 4—4 70 75 of Fig. 1; and Fig. 5 is an enlarged cross-sectional view taken through the clutch mechanism substantially along the line 5—5 of Fig. 4.

Referring to the drawings in Figs. 1 and 2, 10 indicates an integrally formed fan and nozzle casing, the fan casing portion 11 being provided with an offset or tangentially formed elbow 12 to afford a large rearwardly extending air passageway 13, the elbow turning downwardly to be in line with a peripheral enlargement of the fan chamber. I prefer to form the air passageway at as low a level as is practically possible and I accordingly arrange the entire mechanism to obtain a low disposition of the exhaust port relative to the nozzle opening as will be hereinafter set forth.

The elbow portion 12 of the fan casing terminates in an annular flange 19 which may be a part of a back plate of the casing. About half of this flange is behind the region in which the fan revolves. There is, therefore, a large exhaust port leading directly from the fan region. This flange 19 may be provided with any suitable dust bag connecting means for attaching a dust bag 14 thereto. A preferred form of connection may be a metallic ring 15 having a cylind-

drical portion 16 engaging the bag fabric in a dust proof, clamped relation and a coniform portion 17 adapted to engage a complementary surface of a coniform flange on the elbow member 12. The ring 15 is slotted to provide a bayonet lock joint as indicated at 18 of Fig. 1.

The nozzle portion 20 of the fan casing 10 extends forwardly and downwardly from 10 the front wall 21 of the fan casing portion 11 and may be flared outwardly from the fan casing to provide an elongated nozzle opening 24. The opposite ends of the nozzle portion of the casing may be suitably formed 15 to receive and house rollers or wheels 25 supporting the forward part of the cleaner casing with the nozzle opening in proper relation to the surface to be cleaned.

The air passageway extending from the 20 nozzle opening 24 into the fan casing may terminate in a large circular opening indicated at 27 and which may be concentric relative to the center of the fan 30. I show the fan casing and nozzle as being formed 25 integrally but these casing portions may be separate members suitably jointed in any convenient manner.

If desired, a brush 32, may be disposed 30 within the nozzle with the bristles thereof extending through the nozzle opening 24 to contact with the surface to be cleaned, and may be mechanically driven, through gear connections, by the forward wheel members 25 in the manner I have described and 35 claimed in my patent application No. 643,041, filed June 2, 1923.

The mechanical motor for driving the suction fan may be a simple mechanism completely housed by a detachable portion of 40 the suction cleaner casing whereby the accurate assembling of the respective parts of the motor mechanism and the fan may be greatly facilitated during the manufacturing thereof. I accomplish this result by arranging the rear portion of the cleaner casing in such manner that the fan 30 may be assembled upon a horizontally disposed shaft 31, during the assembling of the mechanical motor on a detachable housing 50 which may carry all the elements of the motor including the shaft. I therefore, provide a large opening in the rear wall 33 of the fan housing portion of the casing 10 which is of sufficient dimension to receive 55 or permit insertion of the fan in the casing when the fan is mounted upon the shaft 31.

To simplify the motor mechanism referred to, I form a worm 35 directly on the shaft 31, the shaft 31 being enlarged in 60 diameter for this purpose and for the purpose of forming bearing shoulders as indicated at 36. The shaft is supported on bearings indicated at 37 which are positioned in suitable bearing portions 38 65 formed on the forward and rearward walls

40 and 41 respectively of a casing member 42, the latter completely enclosing as well as supporting the mechanical motor. Actuation of the worm is accomplished by a driving member in the nature of a worm wheel 70 or helical gear 43 which is mounted upon a transverse shaft 44. This shaft is rotatably mounted in bearing sleeves 45 and 46 carried by the casing member 42. The driving gear 43 is rotatably supported upon the 75 transverse shaft 44, as stated above, but is rotatable independently of the latter and is drivably connected thereto through a one-way clutch mechanism.

The clutch mechanism may comprise a 80 cup-shaped annular member 52 attached to a hub portion of the driving gear 43 by bolts 54, a sleeve member 55 rigidly secured to the transverse shaft 44 by any suitable means such as a taper pin 56, a pair of disc 85 members 57 rigidly mounted on the sleeve 54, a roller member 58 (see Fig. 5) which are carried by and disposed within notches 59 formed about the perimeter of the disc members 57. The latter members and the 90 sleeve 56 comprise the driving portion of the clutch. To maintain the rollers in place as well as in proper alignment whereby the axis thereof will at all times be parallel with the axis of the shaft 44, I provide a thin disc 62 disposed between the two clutch discs 57 and which is of sufficient diameter to extend radially into the notches 59. This centrally disposed disc member 62 may engage the rollers in grooves 58a formed therein, thus preventing lateral displacement of the rollers. Rigidly mounted on each end of the shaft 44 are driving wheels 65 and 66 which may be secured thereto by pin members 67, see Fig. 4.

The top wall of the motor casing 42 may comprise a removable closure member which may slidably engage suitable grooves formed in the casing or if desired may be held in place by pin or screw members (not shown). To attach the mechanical motor when assembled on the casing member 42, I provide a fan casing closure member in the nature of a plate such as is indicated at 76 in Fig. 3, to which the casing member 42 105 may be secured by screw members 77. Laterally extending screw lugs 78 may be formed on the casing side walls 47 and 48 in positions which permit accessibility to the screws 77. It will thus be understood that 110 the plate 76 serves as an intermediate attaching means extending between the housing or casing member 42 and the nozzle and fan casing 10 and that it should be in assembled relation to the casing member 42 115 before the fan 30 is attached to the fan shaft 31.

Since the fan overlaps the exhaust port 13, due to the latter being positioned close to the fan casing inlet to obtain a direct air 120

passageway from nozzle to bag, I find it preferable to cut away those portions of the fan disc 30^a which would overlap and obstruct the exhaust port. Hence as shown 5 in Fig. 4, the edges 30^b of the disc which are intermediate the blades may have a contour which conforms to the circular wall of the passageway.

A suitable bail 72 may span the motor 10 casing 42 and may be pivotally attached thereto by screw members 73, the latter being properly shouldered to permit the tightening and securing thereof to the casing 42 while permitting a free swinging movement 15 of the bail when swung by a handle 74 secured to the top thereof.

It will be noted that in my present motor construction there are only two shafts which must be properly aligned whereby 20 a high degree of efficiency will be obtained in the power transmission from the driving gear 43 to the worm 35. This accuracy in aligning the shaft members 31 and 44 is greatly simplified in the manufacturing 25 process by having the bearing members or portions for the respective shafts all formed on the casing member 42 whence the bored openings which receive the various bearing or journal members for the shafts, may be 30 completed while the housing member 42 is carried in a boring fixture. Thus, it will be seen that the bearings for the fan shaft 31 may be positioned in suitable bored openings which are formed from the rear end 35 of the casing 42 and in one boring operation, whence the inner bearing member 37 may be readily pressed in place while the outer bearing member 37^a may be retained by a closure plug 70 which engages the end 40 of this bearing member. This arrangement also contributes an adjustable characteristic whereby bearing member 37^a may be properly adjusted lengthwise of the fan shaft 31 to eliminate all play between the 45 fan shaft and the bearing balls 37^b. It will also be noted that the openings formed in the casing for the reception of the bearing sleeves 45 and 46 may likewise be effected in one boring operation, while the housing or 50 casing 42 is positioned in the same boring fixture. This arrangement of the shaft bearings is an important characteristic of my invention as it greatly decreases the cost of manufacturing and assures the highest 55 degree of efficiency in the transmission of power between the driving gear 43 and worm 35 as hereinbefore stated.

From the foregoing description it is readily apparent that many advantages are to be derived by the use of the foregoing described vacuum cleaner construction for a cleaner which is mechanically operated. The simplicity of the parts, the facility with which the parts may be manufactured 60 and assembled due to this simplicity and

the distinct advantage of minimum resistance to the suction action of the fan due to the provision of unusually large unobstructed passageways, all add to the efficient operation of such an economical structure. 70

I claim:

1. A suction cleaner having in combination a fan chamber, a suction nozzle in front thereof, and a gear housing at the rear thereof, said suction nozzle communicating 75 with a fan chamber by an entrance opening adjacent the center of the chamber, there being an exhaust port in the rear wall of the fan chamber itself surrounded by a rearwardly extending annular flange about 80 half of which is directly at the rear of the region in which the fan revolves, while the rest of the flange is connected with the fan chamber by an elbow, which turns downwardly to be in line with a peripheral enlargement of the fan chamber, and a fan 85 within the fan chamber directly behind the entrance opening and overlapping the exhaust port.

2. In a suction cleaner of the type described, the combination of a fan on a fore-and-aft horizontal shaft, a fan casing in the form of a vertical drum with substantially parallel front and back, and a nozzle member communicating with the central region 90 of the front, said fan casing having an upwardly and rearwardly extending elbow 95 providing a rearwardly discharging exhaust port at the back, which exhaust port is located at one side of the vertical plane 100 of the fan axis, above the horizontal plane through such axis and close enough to the fan shaft so that the inner portion of the exhaust port overlaps the region in which the fan revolves, a gear casing at the rear 105 of the fan casing, and means mounted on the gear casing for rotating the fan.

3. In a suction cleaner, the combination with a fan casing and a suction nozzle communicating therewith, of a detachable plate 110 forming the rear wall of the fan casing and provided with an opening surrounded by a rearwardly extending annular flange to make a discharge passage from the fan chamber, a gear casing secured to said removable closure plate, a fan shaft journaled in the gear casing and projecting into the fan chamber, a fan on the fan shaft within the fan chamber, and means for driving the fan shaft. 115

4. In a suction cleaner, the combination with a fan casing and a suction nozzle communicating therewith, of a detachable plate 120 forming the rear wall of the fan casing and provided with an opening surrounded by a rearwardly extending annular flange to make a discharge passage from the fan chamber, a gear casing removably secured to said removable closure plate and removable as a unit therefrom, said gear casing 125 130

having a front and rear wall, a fan shaft journalled in bearings in the front and rear wall of the gear casing respectively and projecting into the fan chamber, a fan on the fan shaft within the fan chamber, a transverse driving shaft journalled in bearings in the side walls of said removable gear

casing, and driving gearing within the gear casing connecting said transverse shaft with the fan shaft and including an over-run-
ning clutch. 10

In testimony whereof, I hereunto affix my signature.

WILLIAM E. SHERBONDY.
